(57) **CLAIM**

The ornamental design for a ring toss game, as shown and described.

DESCRIPTION

FIG. 1 is a front, top perspective view of a ring toss game showing my design in an assembled state;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front top perspective view showing the ring toss game in an exploded state; and,

FIG. 10 is another front top perspective view showing the ring toss game in a slightly larger scale and in an assembled state.

The broken lines in the drawings illustrate the portions of the ring toss game, which form no part of the claimed design.
